CIGARETTE LIGHTER

Irving Florman, New York, N. Y.

Application July 30, 1935, Serial No. 33,879

6 Claims. (Cl. 67—7.1)

My invention relates to cigarette lighters, and more particularly to lighters of the flint-wheel type.

The primary object of the invention is to provide a lighter of this type which opens and ignites by a simple pushing motion of the thumb. Particularly, this result is accomplished by the lifting of a cover by the thumb, this lifting action causing ignition of the wick. Furthermore, the cover remains open so that the lighter stays lit without further control by the user.

Another object of the invention is to provide a lighter which is entirely safe, and which is so arranged that it will not ignite accidentally under any circumstances, but only when it is deliberately opened by the user.

A further object of the invention is to provide a lighter of this type which imparts a sudden jerk to a flint wheel, no matter how the cover may be operated manually, so as to cause proper movement of the flint-wheel against the flint and thus to cause the ignition whenever the lighter is operated.

An additional object of the invention is to provide an arrangement in which a member separate from and having a one-way connection with a flint wheel is latched against movement while the cover is being opened, during which operating movement a spring tension is placed on the movable member, and then is released suddenly as the cover reaches or approaches its fully open position. More particularly, my invention contemplates the use of a separate snuffing member for covering the wick as such an element.

Such an arrangement is particularly desirable since it makes it unnecessary to lock the flint wheel itself against movement and since it ensures proper operation of the spring and flint wheel.

Still another object of the invention is to provide a novel type of extinguishing element which will operate properly despite any wear which may occur in the lighter.

Further objects and advantages of the invention will appear more fully from the following description, particularly when taken in conjunction with the accompanying drawing which forms a part thereof.

50 In the drawing:

Fig. 1 shows in side elevation the lighter according to my invention with the cover partly raised by the hand of the user.

Fig. 2 is a front view of the lighter in open or ignited position.

Fig. 3 is a side view with parts broken away of the upper portion of the lighter with the cover closed.

Fig. 4 is a cross section on the line 4—4 of Fig. 2.

As shown in the drawing, the lighter comprises a body portion or casing 2 forming a reservoir or fuel chamber, this being filled with some absorbent material 4 such as cotton. This reservoir may be filled from the bottom through a fuel plug 6. In the top wall 8 of the lighter body is a tube 10 for receiving a wick 12 which extends downwardly through the tube into the cotton within the body 2. A flint tube 14 closed at the bottom by a plug 16 also extends upwardly through the body, and is provided with a spring 18 so as to hold a piece of flint 20 in position in the top wall of the casing.

On either side of the flint, ears 22 extend upwardly from the top wall 8, these ears being spaced inwardly a slight distance from the outer surfaces of the side walls. A cover 24 is pivotally mounted at the lower rear corner of the ears 22, on a pin 26.

In the ears 22 is mounted a transverse shaft 28. A flint wheel 30 is rotatably mounted on said shaft in a position to engage the flint 20. The invention provides means whereby the raising of the cover will cause such flint wheel to turn and strike sparks from the flint onto the wick thereby igniting the same.

Pivoted on the shaft 28 is a snuffer member 32 having a snuffing portion 34 arranged at such a distance from the shaft 28 as to cover the wick when the snuffer member is depressed. The snuffer member has leg or bearing portions 36 on each side of the flint wheel 30 which bear on the shaft 28. On the inner face of one of these members 36 is arranged a spring tooth 38 which is adapted to cooperate with ratchet teeth 40 on the adjacent side wall of the flint wheel 30. This forms a one-way connection between the snuffer member and the flint wheel, so that when the snuffer member is raised it will impart motion to the flint wheel, while during its movement toward covering position the flint wheel may remain stationary.

In order to impart motion to the snuffer member when the cover is raised, it is provided with an upstanding portion 42 to which is attached a coil spring 44 the other end of which is connected to a rod or pin 46 mounted adjacent the top of the cover 24. However, the snuffer member is normally held against movement by a shoulder or notch 48 provided in one of the members 55

36 and which may be engaged by a pin 50 on a latch member 52 pivoted on pin 26. A spring 56 normally holds this latch member in such position that the pin 50 engages beneath the shoulder 54 and thus locks the snuffer member against movement towards uncovering or raised position.

The latch member 52 also has an upward extension 58 which lies in the path of movement of a pin or post 60 mounted on the inside wall of the cover 24.

The operation of this arrangement is as follows: When the user wishes to ignite the wick, he pushes the cover upwardly with his thumb in the general manner shown in Fig. 1 in the direction of the arrow. As the cover rises, the spring 44 is placed under tension because the pin 46 moves away from the portion 42 of the snuffer member. The snuffer member is held down because the pin 50 of the latch 52 is engaged beneath the shoulder 48. When the cover reaches or approaches open position, the pin 60 strikes the upward extension of latch 52 and pushes pin 50 out of engagement with shoulder 48. The snuffer member is now free to rise, and the spring 44 will pull it to uncovering position. As the snuffer member moves upwardly, because of its one-way connection with the flint wheel it imparts a sudden spinning motion to the flint wheel which throws sparks against the wick and ignites the same.

30 When the user wishes to extinguish the flame and restore the lighter to a condition for further operation, the cover is depressed. As the cover begins to move downwardly, its front wall engages the front wall of the snuffing portion 34 and 35 pushes the same downwardly. As the cover and snuffer approach closed position, the snuffing portion 34 swings out of the path of the front wall of the cover, but at the same time pin 46 engages upward extension 47 of the snuffer member and 40 forces the same downwardly into the position shown in Fig. 3. The tension of spring 44 is now sufficient to hold the cover closed, since latch member 52 has moved under the action of its spring and the pin 50 has again engaged beneath shoulder 48 to lock the snuffer member in place. 45

50 From the above description, it is evident that in order to operate the lighter all that is necessary is to hold the body of the lighter in the hand and raise the cover with the thumb in the manner indicated in Fig. 1. In order to extinguish the lighter the cover is moved back, for example with the forefinger, to closed position. The tension of the spring will hold the lighter closed, until pressure is again exerted by the thumb to open it.

55 While I have described herein one embodiment of my invention, I wish it to be understood that I do not intend to limit myself thereby except within the scope of the appended claims.

I claim:

60 1. In a cigarette lighter, a wick, a rotatable flint wheel, means to hold a flint in engagement with said wheel, a pivoted snuffer member, having a snuffer portion adapted to cover and uncover said wick, a one-way connection between said snuffer member and said flint wheel, a cover movable to cover and uncover said flint wheel and snuffer member, a spring having one end connected to said snuffer member and the other end connected to said cover, means to hold said snuffer member against movement, and means operated by movement of said cover as it approaches open position to release said holding means, whereby raising of said cover first places said spring under tension while said snuffer member is held in closed position, and then releases the snuffer member

so that the same is moved suddenly by said spring and imparts a sudden rotation to the flint wheel.

2. In a cigarette lighter, a casing, a wick mounted in said casing, a shaft mounted on said casing, a flint wheel mounted on said shaft, means to hold a flint in engagement with said wheel, a snuffer member pivoted on said shaft, and further having a snuffer portion adapted to cover and uncover said wick, a one-way connection between said snuffer member and said flint wheel, a cover pivoted on said casing and enclosing said flint wheel and said snuffer member, a spring having one end connected to said snuffer member and the other end connected to said cover, means to hold said snuffer member against movement, and means operable by movement of said cover as it approaches open position to release said holding means, whereby raising of said cover first places said spring under tension while said snuffer member is held in closed position, and then releases the snuffer member so that the same is moved suddenly by said spring and imparts a sudden rotation to the flint wheel. 5 10 15 20

3. In a cigarette lighter, a casing, a wick mounted in said casing, a shaft mounted on said casing, 25 a flint wheel mounted on said shaft, means to hold a flint in engagement with said wheel, a snuffer member having bearing portions pivoted on said shaft on either side of said flint wheel and further having a snuffer portion adapted to cover and uncover said wick, a one-way connection between said snuffer member and said flint wheel, a pivoted latch member, cooperating means on said snuffer member and latch member to hold the snuffer member against rotation, a cover pivoted on said casing and enclosing said flint wheel and said snuffer member, a spring having one end connected to said snuffer member and the other end connected to said cover, and means operable by movement of said cover as it approaches open position to shift said latch member, whereby raising of said cover first places said spring under tension while said latch member holds said snuffer member in closed position, and then shifts said latch member to release the 45 snuffer member so that the same is moved suddenly by said spring and imparts a sudden rotation to the flint wheel.

4. In a cigarette lighter, a casing having a fuel chamber therein, and having a top wall, a wick 50 extending through the top wall of the said casing and communicating with said fuel chamber, a flint mounted in the top wall of the casing, ears upwardly extending from the top wall of the casing, a shaft mounted in said ears, a flint wheel 55 mounted on said shaft in engagement with said flint, a snuffer member, portions pivoted on said shaft on either side of said flint wheel, and further having a snuffer portion adapted to cover and uncover said wick, a spring pawl on the inner wall of one of said bearing portions, said flint wheel having inclined teeth on the side thereof adjacent said spring pawl so as to form a one-way connection between said snuffer member and said flint wheel, a pivoted latch member, cooperating means on said snuffer member and latch member to hold the snuffer member against rotation, a cover pivoted on said casing and enclosing said flint wheel and said snuffer member, a spring having one end connected to said snuffer 70 member and the other end connected to said cover, and means operable by movement of said cover as it approaches open position to shift said latch member, whereby raising of said cover first places said spring under tension while said latch 75

member holds said snuffer member in closed position, and then shifts said latch member to release the snuffer member so that the same is moved suddenly by said spring and imparts a sudden rotation to the flint wheel.

5. In a cigarette lighter, a casing, a wick mounted in said casing, a shaft mounted on said casing, a flint wheel mounted on said shaft, means to hold a flint in engagement with said wheel, a snuffer member having bearing portions pivoted on said shaft on either side of said flint wheel and further having a snuffer portion adapted to cover and uncover said wick, a spring pawl on the inner wall of one of said bearing portions, said flint wheel having inclined teeth on the side thereof adjacent said spring pawl so as to form a one-way connection between said snuffer member and said flint wheel, a pivoted latch member, cooperating means on said snuffer member and 10 latch member to hold the snuffer member against rotation, a cover pivoted on said casing and enclosing said flint wheel and said snuffer member, a spring having one end connected to said snuffer member and the other end connected to said cover, and means operable by movement of said cover as it approaches open position to shift said latch member, whereby raising of said cover first places said spring under tension while said latch member holds said snuffer member in closed position, and then shifts said latch member to 15 release the snuffer member so that the same is moved suddenly by said spring and imparts a sudden rotation to the flint wheel.

6. In a cigarette lighter, a casing having a fuel chamber therein, and having a top wall, a wick

extending through the top wall of the said casing and communicating with said fuel chamber, a flint mounted in the top wall of the casing, ears upwardly extending from the top wall of said casing, a shaft mounted in said ears, a flint wheel mounted on said shaft in engagement with said flint, a snuffer member, portions pivoted on said shaft on either side of said flint wheel, and further having a snuffer portion adapted to cover and uncover said wick, a spring pawl on the inner wall of one of said bearing portions, said flint wheel having inclined teeth on the side thereof adjacent said spring pawl so as to form a one-way connection between said snuffer member and said flint wheel, said snuffer member having a shoulder at the rear side thereof, a pivoted latch member having a pin engageable beneath said shoulder, a spring normally holding said latch member in a position in which said pin is beneath said shoulder, a cover pivoted on said ears, and enclosing said flint wheel and said snuffer member, a spring having one end connected to said snuffer member and the other end connected to said cover, said latch member having an extension thereon, and a pin on said cover engageable with said extension when said cover moves towards open position to shift said latch member, whereby raising of said cover first places said spring under tension while said latch member holds said snuffer member in closed position, and then shifts said latch member to release the snuffer member so that the same is moved suddenly by said spring and imparts a sudden rotation to the flint wheel.

IRVING FLORMAN. 35
